UNITED STATES PATENT OFFICE.

RUSSELL J. WITTMER, OF CLEVELAND, OHIO, ASSIGNOR TO NATIONAL MALLEABLE ·
AND STEEL CASTINGS COMPANY, OF CLEVELAND, OHIO, A CORPORATION OF OHIO.

CAR COUPLER.

Application filed April 21, 1925. Serial No. 24,720.

Fig. 1 is a vertical, longitudinal section of the coupler embodying my invention, with the parts in locked position; Fig. 2 is a section similar to Fig. 1, but with the lifter raised to free the auxiliary anti-creep provisions; Fig. 3 is also a section similar to Fig. 1, but with the parts in lock-set position; Fig. 4 is a detail of the lifter, and Figs. 5 and 6 details of the anti-creep member; Fig. 7 shows a modified form of lifter, and Figs. 8 and 9 the form of anti-creep member used in connection therewith.

My invention relates to car couplers, and particularly to improvements applicable to the standard **D**-coupler. In couplers of the standard **D**-type difficulty is had with the lock-to-lock or anti-creep provisions, especially where the couplers are used for fast service on roads with uneven road-beds, or in which the draft gear attachments permit vibration of the coupler in a vertical direction. With my improved mechanism, however, even under the severest conditions of service, means are provided for insuring that the locking action of the anti-creep means shall be positive. My invention also comprises the features which I shall hereinafter describe and claim.

Referring to the drawings, I have shown my invention applied to a standard **D**-coupler comprised of the coupler head A, the knuckle B, the lock C, opener D, and lifter E. The lifter E is of the same general external form as that required in the standard **D**-coupler, with the usual anti-creep shoulder 2 at its lower end, which underlies and engages the transverse rib 3 on the coupler head when in locked position. The upper end of the lifter, however, has a vertically extending recess 4 in which the anti-creep member 5 operates. At the upper end of the lifter is an elongated transversely extending slot 6, and near the lower end of the slot 4 is a hole for a rivet 7 by which the upward and downward movement of the anti-creep member 5 in the slot 4 is limited. The rivet 7 passes through the inclined slot 8 in the anti-creep member 5 and thus limits not only the downward and upward movements of the anti-creep member 5, but also guides it in its fore and aft movements. The upper end of the anti-creep member 5 is provided with a round hole 9 through which, and likewise through the elongated slot 6, the lower end of the uncoupling mechanism 10 passes.

When the parts are in locked position as shown in Fig. 1, the weight of the uncoupling mechanism 10 or of the anti-creep member 5, or both, forces down the anti-creep member 5 to the lower end of the slot 6 and thus causes the shoulder 11 on the anti-creep member 5 to project forwardly of the front face of the lifter so as to underlie the top wall of the coupler head forward of the lock lift hole 12. Any movement of the coupler which would be sufficiently violent to throw the anti-creep shoulder 2 on the lifter E out of engagement with the anti-creep rib 3 in the coupler head merely brings the shoulder 11 of the anti-creep member 5 into contact with the upper wall of the coupler head and thus prevents the lifter E from moving upwardly far enough to become disengaged from its normal anti-creep rib 3.

In unlocking the coupler, the first upward movement of the uncoupling mechanism 10 raises the anti-creep member 5 relative to the lifter E to the extent provided by the elongated slot 6 in the head of the lifter, and this retracts the lower end of the anti-creep member from beneath the top wall of the coupler head into the recess 4 in the lifter. Then, as the uncoupling mechanism 10 comes into bearing against the upper end of the elongated slot 6 in the lifter E, it will lift the lifter and operate the lock D, with the result that the force required for the lock lifting and knuckle throwing operations is preferably transmitted directly from the operating mechanism 10 to the lifter, and not through the anti-creep member 5.

When the lock is in its lock-set position shown in Fig. 3 and the lifting force has been released from the uncoupling mechanism 10, the anti-creep member will slide back to the same position relative to the lifter that it occupies in its normal locked position, except that the anti-creep member will then be outside of the coupler head, as is shown in Fig. 3. When the lock is again dropped down from lock-set position into locked position shown in Fig. 1, it is, of course, necessary that the anti-creep member 5 be again brought inside the lifter so that it may pass down with the lifter through the top lock lift hole 12 in the coupler head. To effect this the lower front face 13 of the anti-creep member is inclined. As the lifter drops down through the top lock lift hole 12, this inclined surface 13 on the anti-creep member 5 comes

in contact with the upper edge of the top lock lift hole and causes the anti-creep member 5 to slide back into the recess 4 of the lifter E, so that the entire lifter E is free to drop back into locked position.

In Figs. 7, 8 and 9 I have shown a modified form of my invention in which the upper end of the lifter is split at 14, so that the two sides 15 and 16 can be sprung apart and the anti-creep member 5 may be inserted between them. The member 5 has a collar 17 around its uncoupling rod hole and the slots 6' in the sides of the lifter are made sufficiently wide to accommodate the collar 17. After the anti-creep member 5 has been inserted in the lifter, the sides 15 and 16 are held together by a small rivet 18 through the upper ends of the sides. In this form of lifter the lifting force exerted by the uncoupling mechanism is all taken up through the anti-creep member 5 and is transmitted by the collar 17 to the lifter.

While I have shown my improved anti-creep member and means used in conjunction with the usual anti-creep feature of the standard D-coupler, it is to be understood that it is sufficiently positive to be used alone without the present standard D-coupler feature.

30 The terms and expressions herein employed are used as terms of description and not of limitation, and there is no intention, in the use of such terms and expressions, of excluding any mechanical equivalents of the feature shown and described, or portions thereof, it being recognized that various structural modifications are possible within the scope of the invention claimed.

What I claim is:

40 1. In a car coupler of the standard D-type, a lock having a T-slot therein; a lifter for the lock having a trunnioned engagement with the lock in the T-slot thereof; an anti-creep member seated in a vertically extending recess in the head of the lifter; the lifter and anti-creep member having transversely extending apertures for connection with uncoupling mechanism; the lifter and anti-creep member having a slot and projection engagement permitting, when the lifter is in locked position, a portion of said anti-creep member to project outwardly of the lifter to underlie a portion of the top wall of the coupler head; said connection with the uncoupling mechanism comprising means for retracting the anti-creep member out of anti-creep position without disturbing the lifter.

50 2. In a car coupler of the standard D-type, a lock having a T-slot therein; a lifter for the lock having a trunnioned engagement with the lock in the T-slot thereof; an anti-creep member seated in a vertical recess in the head of the lifter; the lifter and anti-creep member having transversely extending apertures

for connection with uncoupling mechanism; the lifter and anti-creep member having a slot and projection engagement permitting, when the lifter is in locked position, a portion of said anti-creep member to project outwardly of the lifter to underlie a portion of the top wall of the coupler head; and means for retracting the anti-creep member within the lifter to permit the lock to be lifted.

3. In a car coupler of the standard D-type, a lock having a T-slot therein; a lifter for the lock having a trunnioned engagement with the lock in the T-slot thereof; an anti-creep member seated in a vertical recess in the head of the lifter; the lifter and anti-creep member having transversely extending apertures for connection with uncoupling mechanism; the lifter and anti-creep member having a slot and projection engagement permitting, when the lifter is in locked position, a portion of said anti-creep member to project outwardly of the lifter to underlie a portion of the top wall of the coupler head; means for retracting the anti-creep member within the lifter to permit the lock to be lifted; and guiding means on the anti-creep member to cause its retraction into the lifter to permit the lifter when in elevated position to drop to locked position.

4. In a car coupler of the standard D-type, a lock having a T-slot therein; a lifter for the lock having a trunnioned engagement with the lock in the T-slot thereof; an anti-creep member seated in a vertically extending recess in the head of the lifter; the lifter and anti-creep member having transversely extending apertures for connection with uncoupling mechanism, the aperture in the lifter being of greater vertical extent than the aperture in the anti-creep member; said connection comprising sequential means for first retracting the anti-creep member and then raising the lifter to lift the lock.

5. In a car coupler of the standard D-type, a lock having a T-slot therein; a lifter for the lock having a trunnioned engagement with the lock in the T-slot thereof; an anti-creep member seated in a vertically extending recess in the head of the lifter; the lifter and anti-creep member having transversely extending apertures for connection with uncoupling mechanism; the lifter and anti-creep member having a slot and projection engagement permitting, when the lifter is in locked position, a portion of said anti-creep member to project outwardly of the lifter to underlie a portion of the top wall of the coupler head; said connection with the uncoupling mechanism having a direct engagement with the anti-creep member to move it out of anti-creep position and with the lifter to lift the lock.
